UNITED STATES PATENT OFFICE.

JOHN F. HINTZ, OF BRILLION, WISCONSIN.

MUFFLER.

1,103,769.

Specification of Letters Patent.

Patented July 14, 1914.

Application filed July 23, 1913. Serial No. 780,747.

To all whom it may concern:

Be it known that I, JOHN F. HINTZ, a citizen of the United States, residing at Brillion, in the county of Calumet and State 5 of Wisconsin, have invented new and useful Improvements in Mufflers, of which the following is a specification.

The present invention provides means for muffling the exhaust of internal combustion 10 engines, being particularly designed for marine or stationary engines, but which may be used to advantage for muffling the exhaust of automobile engines.

The invention provides a muffler embodying a cylinder closed at its ends by means 15 of heads, one of such heads being provided with a plurality of outlets, a drum located within the cylinder, a plate or head closing one end of the drum and adapted to close 20 the outlets in the head of the cylinder provided with the plurality of openings. A spring for holding the drum with its head spaced from the head of the cylinder provided with the plurality of openings, and 25 means for regulating the movement of such drum.

The invention consists of the novel features, details of construction and combination of parts, which hereinafter will be more 30 particularly set forth, illustrated in the accompanying drawings, and pointed out in the appended claims.

Referring to the drawings, forming a part 35 of the specification, Figure 1 is a perspective view of a muffler embodying the invention. Fig. 2 is a longitudinal section of the cylinder and heads, showing the drum and remaining parts in elevation. Fig. 3 is an enlarged sectional view of an end portion 40 of the muffler. Fig. 4 is a detail view of the head of the cylinder provided with the plurality of openings and a raised seat for the drum to close against.

Corresponding and like parts are referred 45 to in the following description, and indicated in all the views of the drawings, by the same reference characters.

The numeral 1 designates the cylinder which is closed at its ends by means of heads 50 2 and 3. Bolts 4 pass through the cylinder and openings formed in the heads 2 and 3 and connect the several parts. The heads are retained in place by means of flanges which embrace the sides of the cylinder 1. 55 The head 2 is provided with a plurality of openings 5 which constitute outlets for the

exhaust gases. A rib of annular form 60 includes the openings 5 and constitutes a seat for the drum to close upon when the exhaust gases are confined within the cylinder. A boss 7 projects outwardly from the head 2 and is externally threaded to receive a tube 8, which is threaded thereon. A cap 9 closes the outer end of the tube 8 and is centrally apertured to receive a rod 10 which is 65 mounted in the boss 7 and has a limited longitudinal movement. The drum 11 is connected with the inner end of the rod 10 and moves therewith. A flat spring 12 is mounted upon the inner end of the rod 10 and 70 comes between the drum 11 and the head 2 and normally exerts a pressure to hold the drum 11 spaced from the head 2 so that the exhaust gases may pass from the cylinder through the openings 5 in the head 2. Stops 75 13 and 14 are mounted upon the rod 10 and limit the movement thereof. The inner stop 13 is adapted to engage the boss 7 and thereby regulate the space between the head of the drum and the inner face of the head 2. 80 The outer stop 14 is adapted to engage the cap 9 and limit the movement of the drum when closing. Each of the stops 13 and 14 consists of a nut which is mounted upon the rod 10. A jam nut co-operates with each 85 of the nuts 13 and 14 to hold the same in the adjusted position. Washers 15 are interposed between the stops 13 and 14 and the parts adjacent such stops to form buffers to prevent any clacking in the movement of the 90 drum.

The drum 11 consists of a cylinder which is open at one end and closed at its opposite end, the closed end being secured to a disk or plate 16, which is adapted to close against 95 the annular rib 6 of the head 2 and thereby confine the exhaust gases within the cylinder. The disk or plate 16 is bolted or otherwise secured to the closed end of the drum 11 and is provided with a raised portion 17, 100 which is adapted to close against the annular rib 6. The annular rib or raised portions 6 and 17 form a space in which the spring 12 is located. An opening is formed in the lower portion of the head 2 for the circulation of water when the muffler is used in connection with a marine engine.

In the operation of the invention the pipe receiving the exhaust from the engine makes connection with the head 3, the latter being 110 provided at a central point with an internally threaded boss to receive such pipe.

When the gases exhaust from the engine and enter the cylinder a pressure is created upon the disk or plate 16, thereby moving the drum to close the openings 5 in the head 2. 5 The cylinder is of a size to receive the exhaust gases and a moment after the gases have entered the cylinder the drum 11 is moved by the action of the spring 12, thereby uncovering the openings 5 to admit of the 10 burnt gases escaping therethrough preliminary to the cylinder receiving the next charge of the exhaust from the engine. The escape is distributed and is so broken up by the openings 5 and by the tortuous passage 15 of the gases around the drum and the part 16 that but little or no noise results from the final discharge of the burnt gases into the air.

It is to be understood that the exhaust 20 gases enter the cylinder 1 with a rush and great force and pass directly into the cylinder 11, thereby moving such cylinder against the tension of the spring 12 to close the head 16 against the head 2. After the inrush of 25 the gases ceases the bulk of the gases practically confined in the cylinder 11 expand into the cylinder 1, thereby materially reducing the pressure to such an extent as to admit of the spring 12 regaining itself and 30 moving the cylinder 11 to carry the head or plate 16 away from the plate 2. This provides an escape for the gases preliminary to the next discharge of the exhaust, which as well known is intermittent.

35 From the foregoing description, taken in connection with the accompanying drawings, the advantages of the construction and of the method of operation will be readily apparent to those skilled in the art to which 40 the invention appertains, and while I have described the principle of operation of the invention, together with the device which I now consider to be the best embodiment thereof, I desire to have it understood that 45 the device shown is merely illustrative, and that such changes may be made when desired as are within the scope of the claims appended hereto.

Having thus described the invention what 50 is claimed as new, is:—

1. In a muffler of the character specified the combination of a cylinder having opposite ends closed and having one of such ends provided with a plurality of openings, a 55 drum arranged within the cylinder and having one end open and the opposite end closed, the closed end being arranged adjacent the end of the cylinder provided with the plurality of discharge openings, said 60 drum being moved upon the entrance of the

exhaust gases into the cylinder to close the openings of the cylinder end, and a spring normally exerting a pressure to move the drum to uncover the openings in the end of the cylinder to provide an escape for the 65 burnt gases.

2. In a muffler of the character specified the combination of a drum having opposite ends closed by means of heads, one of such heads having an inlet to receive the burnt 70 gases and the other one of the heads being provided with a plurality of openings, a drum arranged within the cylinder and having one end closed and its opposite end open, the open end of the drum facing the inlet of 75 the cylinder, and the closed end of the drum being adapted to close the outlets in the head of the cylinder, and a spring arranged to exert a pressure upon the drum to move the same away from the head of the cylinder 80 provided with the discharge openings.

3. A muffler of the character specified comprising a cylinder, heads closing the ends of the cylinder, one of such heads having an inlet to receive the burnt gases and 85 the other head being provided with a plurality of outlets, a drum arranged within the cylinder and having one end open and facing the inlet of the cylinder, a plate closing the opposite end of the drum and adapted 90 to come in contact with the head of the cylinder provided with the outlets to close the latter, and a spring arranged between the head of the drum and the head of the cylinder having the outlets formed therein. 95

4. A muffler of the character specified comprising a cylinder, heads closing the ends of the cylinder, one of such heads having an inlet for the burnt gases and the other head being provided with a plurality 100 of outlets, a rod slidably mounted in the head of the cylinder having the outlets, means for limiting the longitudinal movement of the rod, a drum secured to the inner end of the rod and having one end open and facing the inlet of the cylinder and having its opposite end closed and adapted to abut against the head of the cylinder having the outlets to close the latter, and a spring 105 normally exerting a pressure to hold the head of the drum spaced from the head of the cylinder having the outlets formed therein.

In testimony whereof I affix my signature in presence of two witnesses.

JOHN F. HINTZ.
